UNITED STATES PATENT OFFICE

101,417

DESIGN FOR A FLOWER BASKET OR HOLDER

Howard M. Potter, Youngstown, Ohio

Application December 5, 1934, Serial No. 54,290

Term of patent 3½ years

To all whom it may concern:

Be it known that I, Howard M. Potter, a citizen of the United States, residing at Youngstown, in the county of Mahoning and State of Ohio, have invented a new, original, and ornamental Design for a Flower Basket or Holder, of which the following is a specification, reference being had to the accompanying drawing, forming a part thereof, in which

The single figure is an elevational view of a container or holder embodying my new design as applied to a flower basket.

The article comprises a container or holder of

thin gauge sheet metal with fluted sides, each flute extending for the major part of its length in a straight line and increasing in breadth from the bottom to the top, the rear upper end of the holder being folded or bent outwardly and upwardly, and the forward upper end of the holder being folded or bent outwardly and downwardly, thereby presenting the effect of a fluted collar.

I claim:

The ornamental design for a flower basket or holder substantially as shown and described.

H. M. POTTER.
